C. Kirchhof,

Air Gun,

No 76,925,

Patented Apr 21, 1868.

Inventor:

Charles Kirchhof

United States Patent Office.

CHARLES KIRCHHOF, OF NEWARK, NEW JERSEY.

Letters Patent No. 76,925, dated April 21, 1868.

BLAST-GUN.

The Schedule referred to in these Letters Patent and making part of the same.

TO ALL WHOM IT MAY CONCERN:

Be it known that I, CHARLES KIRCHHOF, of the city of Newark, county of Essex, in the State of New Jersey, have invented a new device, termed the "Blast-Gun," imitating the sound of fire-arms and propelling objects.

The nature of my invention consists in the construction of a device and the use of means of producing the sound and propelling practice of fire-arms at a very small expense, and, at the same time, without doing any possible harm, combining the two offices, as being (in a diminutive form) a very amusing toy for children; in an enlarged one, a useful apparatus for the production of the sound of a gun.

The principle of my invention consists in producing the sound by bursting a sheet of some material hermetically covering the aperture of an apparatus, by means of compressed air, or any other gas contained in the apparatus, so as to act with a power increasing sufficiently as to cause its final bursting, and, by doing so, to permit the air to escape rapidly, imitating the report of the firm-arm, and propelling, at the same time, sundry objects, if desired.

For materials to be used, I propose hard and well-sized paper, bladder, catgut, mica, isinglass, or foil of gelatine; thin plates of ivory, bone, hard India rubber, tough leaves of trees and flowers, or any other equivalent of similar elasticity and frangibility and form.

For compressing the air and gases by mechanical means, I use a common air-pump, with a reservoir, if so desired; for instance, when to be used as a toy, a pop-gun may answer, but, in case the compression has to be caused by chemical action, the apparatus consists in a gas-generator, say such as are used in the manufacturing of soda-water.

Thus the air or gas has, in both ways, no other chance of escape, unless it bursts the paper or its equivalent. The arrangement of placing the paper or its equivalent so as to prevent the escape of gas or air from any of the apparatus used is somewhat similar to that of the breech-loading gun or revolver, allowing, instead of the cartridge to be inserted, the paper or its equivalent to be placed at the end of the barrel or its equivalent.

The following simple construction of a complete apparatus will illustrate the principle and use of my invention.

Figure 1 is a perspective view of the apparatus.

Figure 2 shows a section dividing the same along its axis.

a represents a metal tube, made of tinned sheet iron, with a metallic ring, *b*, at its end; and the piston *c*, with the handle, *d*, is for compressing and forcing the air along the tube, through the aperture *e e'* of the rings *b f*.

The plane of said ring is covered by a ring, *g*, made of thin, soft India rubber, leather, or any equivalent, and upon which rests the sheet material, *h*, which closes the aperture *e* by the pressure of a second ring, *f*. Said ring is in continued connection with the metallic ring *b*, and of the same size, and is pressed against the latter by the action of the spiral spring *i* acting against the lever *k*, forming an additional part of the ring *f*, and serving to remove the ring *f* from the ring *b* temporarily, by pressing the lever *k* towards the tube *a*, in order to insert the sheet *h*.

At the opposite side of the periphery of the ring *f* is a second hinge, *l*, keeping a long hook, *m*, which serves to hold both rings close upon each other, when taking hold at the projecting part, *n*, on the ring *b*, in order to compress the sheet *h*, to be bursted by the blast of the air forced through the rings, and thus the combination forming a compact whole, giving the air or gas no other chance of escape but through the instant removal of all that obstructs the passage, causing a loud report. To increase or change such report to sounds less disagreeable, or to propel objects, I make an additional extension to the ring *f*.

In the first case, said ring, in whatever shape it may be, serves as a mouth-piece to said extension, which may be shaped into a conical or other form, as, for instance, like that of a speaking-trumpet, fig. 2, *o*.

In the second case, I add a cylinder, (fig. 1,) *p*, in which the object, *q*, may be placed and propelled after the sheet is bursted, in which case the latter serves as a valve.

Suppose a balloon of India rubber, *r*, a parachute, &c., made of light silky material, having a mouth-piece, *s*, closely fitting on the cylinder, the compressed air of the pump or the hydrogen of a generator will, after the discharge, immediately inflate the object, and blow it up into the air, according to the size and power of the pump.

It is obvious that the effect will be increased by the size of the apparatus, the thickness of the material, and the pressure of the air or gas.

Having now described my invention, I will proceed to state what I desire to secure by Letters Patent, viz:

1. I claim the combination of a sheet or plate, *h*, made of the material as herein described, with an apparatus for compressing air or gas, when said sheet or plate is secured hermetically to the latter, by means of an arrangement allowing a speedy removal and restoration of such sheets, in the manner and for the purpose specified.
2. The peculiar construction and connection of the parts *b f g* of the device, for securing the sheet, as set forth.
3. The extension *p* and *o*, made in the manner and for the purpose specified.

CHARLES KIRCHHOFF.
